UNITED STATES PATENT OFFICE.

DENNIS S. BLUE, OF FREMONT, OHIO.

IMPROVEMENT IN WASHING-MACHINES.

Specification forming part of Letters Patent No. 124,322, dated March 5, 1872.

To all whom it may concern:

Be it known that I, DENNIS S. BLUE, of Fremont, in the county of Sandusky and in the State of Ohio, have invented certain new and useful Improvements in Washing-Machines; and do hereby declare that the following is a full, clear, and exact description thereof, reference being had to the accompanying drawing and to the letters of reference marked thereon making a part of this specification.

The nature of my invention consists in the construction and arrangement of a wash-boiler, as will be hereinafter more fully set forth.

In order to enable others skilled in the art to which my invention appertains to make and use the same, I will now proceed to describe its construction and operation, referring to the annexed drawing, in which—

Figure 1 is a plan view, and Fig. 2 a longitudinal vertical section of my boiler.

A represents a boiler of any desired shape and dimensions, provided with an interior removable agitator, so as to wash the clothes by boiling, agitation of the water, and the squeezing of the clothes. The agitator consists of four perforated plates, B B and C C, of metal or other suitable material. The two plates B B are hinged together at *a*, as shown, and the plates C C are hinged to the plates B B at *b*. To the free ends of the plates C C are attached wire hooks *d d*, which are placed on the edges of the boiler, and held at or near the center of the same by wires *e e*. To the ends of the connection or hinge *a*, between the two plates B B, are attached rods *f f*, the upper ends of

which are attached to the ends of a forked lever, D. The forks of this lever are pivoted on pins at the ends of a cross-bar, E, secured on top of the boiler at one end, as shown.

The clothes are placed inside of the agitator, and also underneath; and, by working the lever D up and down, the water is agitated and the clothes squeezed or pressed.

The agitator, instead of being made of perforated plates, as above described, may be made in four pieces or parts, each part consisting of slats suitably connected. The hooks or rods *f f* may be unhooked from the lever D and the forks of said lever spread apart to release them from the pins or journals on the cross-piece E. Then by turning back the wires *e e* the entire agitator can be readily removed, or opened and closed.

Having thus fully described my invention, what I claim as new, and desire to secure by Letters Patent, is—

The combination of the perforated plates B B and C C, or their equivalents, hinged together at *a* and *b b*, and attached to the boiler A by means of the hooks *d d* and wires *e e*, and operated by the lever D, substantially as and for the purposes herein set forth.

In testimony that I claim the foregoing I have hereunto set my hand this 19th day of January, 1872.

D. S. BLUE.
